UNITED STATES PATENT OFFICE.

WILLIAM H. BOORMAN, OF JERSEY CITY, NEW JERSEY.

DESIGN FOR AN EMBLEM.

51,536.

Specification for Design.

Patented Dec. 4, 1917.

Application filed August 1, 1917. Serial No. 183,993. Term of patent 3½ years.

To all whom it may concern:

Be it known that I, WILLIAM H. BOORMAN, a citizen of the United States, residing at Jersey City, in the county of Hudson and State of New Jersey, (whose post-office address is No. 72 St. Pauls avenue, Jersey City, New Jersey,) have invented a new, original, and ornamental Design for Emblems, as shown in the accompanying drawing and described in the following specification.

The figure is a plan view of an emblem showing my new design.

I claim:

The ornamental design for an emblem as shown.

WILLIAM H. BOORMAN.

Witnesses:

FRANK P. WOGLOM.
NORA A. NORTON.
